UNITED STATES PATENT OFFICE

MILLARD B. LUCKER, OF BENTON HARBOR, MICHIGAN, ASSIGNOR TO AUTO SPECIAL-TIES MFG. CO., OF SAN FRANCISCO, CALIFORNIA, A CORPORATION OF CALIFORNIA

LIFTING JACK

Application filed December 19, 1928. Serial No. 326,923.

My invention relates to lifting jacks and particularly to jacks adapted for use in connection with vehicles such as automobiles.

One of the primary objects of my present invention is to provide a lifting jack of simple and durable construction which may be conveniently moved into operative position beneath a vehicle such as an automobile and operated with considerable ease through the agency of a lever arm extending outwardly from the actuating parts of the jack.

Another object of my invention is to provide a lifting jack, as above set forth, in which the actuating parts are of very simple design and may be very easily assembled or disassembled, thereby providing a device which is practical from the standpoint of manufacture and which may readily be disassembled for purposes of repair or replacement of parts.

More specifically, my invention contemplates the provision of a lifting jack in which a pawl and ratchet mechanism is employed to effect the movement of the work engaging member, said pawl and ratchet mechanism being conveniently mounted between the side frames and at the lower portions of said jack, conveniently operable means being provided on the actuating handle of the jack for controlling the actuation of said mechanism.

Still more specifically, my invention contemplates the provision of a jack which is mounted upon a carriage to render the same readily adaptable for positioning beneath an automobile, said carriage supporting a pawl and ratchet mechanism which may be operated by means of an outwardly extending handle or lever arm, a shiftable means being associated with said pawl and ratchet mechanism which is operable, through the agency of a control lever on the operating handle, to control the direction of movement of the work engaging portion of the jack.

With the foregoing and other objects in view which will appear in the following description, the invention resides in the novel combination and arrangement of parts and in the details of construction hereinafter described and claimed.

In the drawings:

Figure 1 is a side elevational view of a lifting jack embodying features of my invention, the same being shown in condition to be operatively positioned beneath an automobile or other device to be elevated;

Figure 2 is a plan view of the device shown in Figure 1;

Figure 3 is an enlarged vertical sectional view taken substantially along the line 3-3 of Figure 2;

Figure 4 is an enlarged fragmentary view of the pawl and ratchet mechanism, disclosing the relative position of the parts when the actuating lever is about to be raised to cause the downward movement of the work engaging member;

Figure 5 is a view similar to Figure 4 disclosing the position of the parts constituting the pawl and ratchet mechanism when the lifting pawl has been completely disengaged from the ratchet quadrant and the locking pawl moved into operative position therewith; and

Figure 6 is a fragmentary detailed view of the pawl and ratchet mechanism as viewed from beneath said mechanism.

Referring now more in detail to the drawings wherein like numerals have been employed to designate similar parts throughout the various figures, it will be observed that one embodiment of my invention contemplates the provision of a jack which includes a pair of side frames 10 which are spaced between and mounted at one extremity of a shaft 14. These shafts 12 and 14 support suitable rollers 16. Thus the side frames and rollers present a carriage which is adapted to be conveniently moved from place to place. The upper portions of the side frames 10 converge to form bearings 18 in which a shaft 20 is supported, said shaft providing the means of support for a ratchet or quadrant 22. This ratchet or quadrant 22 comprises a plurality of ratchet teeth 24 and is provided with a lifting arm 26. The outer extremity of this arm 26 pivotally supports a work engaging or lifting member 28. This member 28 is provided with depending arms 30. These arms 30 are pivoted medially thereof to the lifting arm

26 by a pin 32 and the lower extremities of these depending arms are pivotally connected at 34 to one end of a pair of links 36. The opposite ends of these links 36 are rotatably mounted upon a stud 38 extending through the side frames 10. By employing these links 36 the horizontal position of the work engaging member 28 is constantly maintained as said member is moved in response to the actuation of the quadrant 22. Likewise these links 36 provide an additional means for lending rigidity and support for the lifting arm 26.

Actuation is imparted to the quadrant 22 through the agency of an operating or actuating handle 40. This operating handle 40 extends outwardly from the mechanism just described in a convenient position to be actuated by the user, the inner extremity of said handle being pivoted upon a shaft 42 which extends between and is mounted within the side frames 10. Extending laterally and downwardly from the handle 40 adjacent the shaft 42 is a short arm 44, the lower extremity of which pivotally supports a lifting pawl 46. The upper extremity of this lifting pawl 46 is formed with teeth 48 which are designed to operatively engage the ratchet teeth 24 in response to a downward movement of the operating handle 40. A coil spring 50 which is secured at one extremity to a pin 52 extending laterally of the pawl 46 and at its other extremity to a pin 54 secured in a fixed position to the side frames 10, constantly urges the teeth of the pawl into operative association with the ratchet teeth 24.

Pivoted upon a stub shaft 56 carried by the side frames 10 is a second pawl 58 which I shall designate as a locking pawl to distinguish from the lifting pawl 46. This locking pawl carries a pin 60 and interposed between this pin 60 and a pin 62 which fastens to the frames 10, is a coil spring 64 which serves to normally urge said pawl in a clockwise direction as viewed in Figures 3 to 5 inclusive. This pawl 58 is formed with teeth 66 which engage the ratchet teeth 24 when the operating handle 40 is moved upwardly so as to disengage the teeth 48 of the pawl 46 from the ratchet teeth as clearly shown in Figure 5. In other words, as the ratchet quadrant 22 is moved in a clockwise or forward direction, as viewed in Figure 3, by successively raising and lowering the operating handle 40, the pawl 58 provides a means for locking the ratchet in position to permit the pawl 46 to be moved rearwardly into successive tooth engaging positions.

In order to control the direction of movement of the quadrant 22 and consequently the direction of travel of the work engaging member 28, I provide a slide bar 68. This slide bar 68 is provided with slots 70 and 72 and extending through these slots are guide pins 74 and 76 respectively. A coil spring 78

which is interposed between the pin 62 and one extremity of the slide bar 68 serves to constantly urge said bar to the left, Figures 3 to 5 inclusive. At the lower right end of the slide bar I provide a lug 80 and this lug 80 is connected to a lever 82, Figures 1 and 2, on the handle 40 by any suitable connecting means such as the flexible chain or link connections 84. When the lever 82 is swung to the right, as shown in Figure 1, the slide bar 68 will occupy its limiting retracted position to the right, Figure 3. When the slide bar occupies this position it will be apparent that clockwise rotation may be imparted to the quadrant 22 in response to the actuation of the handle 40, the pawl 46 serving to move the quadrant, and the pawl 58 serving as a means for locking said quadrant during each successive retraction of the pawl 46.

When the work engaging member 28 has been moved to the required position of elevation and it is desired to cause the lowering of said member, it is only necessary to swing the lever 82 on the handle 40 in a counter clockwise direction as viewed in Figure 1. Movement of the lever 82 in this direction enables the coil spring 78 to effect the forward movement of the slide bar 68 (to the left) as shown in Figure 4. The forward end of the slide bar engages the pin 60 and thereby causes the disengagement of the pawl 58. As the operating arm or handle 40 is subsequently raised, the pin 52 on the pawl 46 engages the lug 80, thereby moving the slide bar out of engagement with the pin 60 so as to permit the coil spring 64 to act upon the pawl 58. Thus when the teeth 48 of the pawl 46 are completely disengaged from the ratchet in response to continued upward movement of the operating handle as clearly shown in Figure 5, the pawl 58 will prevent the downward movement of the lifting member 28 until a new position is assumed by the pawl 46. In this manner the quadrant is intermittently moved in a counter clockwise direction so as to effect the gradual lowering of the member 28. It will thus be apparent that the slide bar 68 which is actuated in response to the movement of the lever 82, serves to control the direction of travel of the quadrant.

In some instances when the jack is not associated with the work, it may be desired to quickly or freely shift the work engaging member 28. For example, suppose that the member 28 occupies its uppermost position out of engagement with the work and it is desired to quickly lower the same. Under these conditions, the pawl 46 will engage the ratchet teeth 24 as shown in Figure 4, and with the slide bar 68 positioned as shown, the pawl 58 will be held out of engagement with the ratchet teeth. If the arm 40 is now raised and no load is applied to the member

28, and the teeth of the lug 48 are moved to the right, Figure 4, said teeth will immediately become disengaged from the ratchet teeth by reason of the pin 52 engaging with the lug 80. In this instance the spring 78 connected to the slide bar, exerts sufficient force against said bar to prevent a rearward movement thereof in response to the engagement of the pin 52 with the lug 80. When 10 the teeth of the lug 46 become entirely disengaged, the work engaging member 28 may be freely moved up or down. It will be clear, however, that as soon as a load is applied to the member 28, the teeth of the lug 15 46 will not become disengaged until the teeth of the lug 58 are moved into engagement with the ratchet teeth. Thus the pressure of the ratchet teeth against the teeth 48 of the pawl 46, which is occasioned by the weight supported by the member 28, is sufficient to prevent the outward displacement of said teeth 48 until the teeth of the pawl 58 assume the position of engagement shown in Figure 5. In other words, pressure of the ratchet teeth 25 against the teeth of the pawl 46, in response to the load carried on the member 28, will serve to positively shift the slide bar rearwardly when the pin 52 engages the lug 80, thereby permitting the locking lug 58 to be 30 moved into operative position with respect to the ratchet teeth.

From the foregoing it will be apparent that my invention provides a lifting mechanism or jack which is particularly adaptable for use in connection with automobiles and vehicles of like nature. The low position to which the work engaging member 28 is adapted to be moved enables the same to be conveniently inserted beneath the work. The 35 arrangement of the side frames and the rollers provides a very rigid carriage which may be easily moved from place to place. The arrangement of the link arm 36 provides a convenient toggle device for maintaining the proper position of the member 28 and likewise provides additional supporting structure for the lifting arm 26. The pawl and ratchet mechanism just described is conveniently positioned within the carriage or side frames and there are no co-operating parts which will readily get out of order. The simplicity of construction and convenient arrangement of these parts enable the same to be very economically manufactured. The 40 slide bar structure provides a very positive means for controlling the direction of movement of the ratchet quadrant and this bar may be actuated from a point which is easily accessible to the user at all times. The arrangement of the constituent parts makes for efficiency in operation and enables the provision of a comparatively heavy duty lifting jack at a low cost.

Having thus described my invention, what

I claim as new and desire to secure by Letters Patent is:

1. In a lifting jack of the class described, a frame, a pawl and ratchet mechanism mounted upon said frame, said mechanism including a ratchet quadrant having a work engaging means, an actuating pawl for moving said quadrant, a locking pawl for engaging the quadrant when the actuating pawl is disengaged, means operable externally of the frame for effecting the actuation of the pawl and ratchet means, and slidable means co-operating with the locking and actuating pawls for controlling the direction of movement of the quadrant. 70

2. In a lifting jack of the class described, a frame, a pawl and ratchet mechanism mounted upon said frame, said mechanism including a ratchet quadrant having a work engaging means, an actuating pawl for moving said quadrant, a locking pawl for engaging the quadrant when the actuating pawl is disengaged, means operable externally of the frame for effecting the actuation of the pawl and ratchet means, and slidable means co-operating with the locking and actuating pawls for controlling the direction of movement of the quadrant, said control means being operable from a point externally of the frame. 80

3. In a lifting jack of the class described, a frame, a pawl and ratchet mechanism mounted on said frame, said mechanism including a quadrant having a work engaging arm, an actuating pawl for moving said quadrant, a locking pawl for engaging the quadrant when the actuating pawl is disengaged, a lever arm connected with said actuating pawl and operable externally of the frame for effecting the actuation of the pawl and ratchet mechanism, slidable means co-operating with the actuating and locking pawls for controlling the direction of travel of the quadrant in response to the actuation of said lever, and means on the lever for controlling the actuation of the direction controlling means. 100

4. In a lifting jack of the class described, a frame, a pawl and ratchet mechanism mounted upon said frame, said mechanism including a ratchet quadrant having a work engaging member, an actuating pawl for moving the quadrant, a locking pawl for engaging the quadrant when the actuating pawl is disengaged, means connected with said actuating pawl and operable externally of the frame for effecting the operation of the pawl and ratchet mechanism, and a horizontally shiftable member operatively associated with said pawls for controlling the direction of movement of the quadrant in response to the actuation of the means connected with the actuating pawl. 115

5. In a lifting jack of the class described, a frame, a ratchet means having a work en- 120

gaging element associated therewith, an actuating handle pivoted to and operable externally of the frame, an actuating pawl movable in response to the actuation of said handle to effect the movement of the ratchet, 5 a pivoted locking pawl for engaging the ratchet when the actuating pawl is disengaged therefrom, and slideable means operable in response to the rearward movement 10 of the actuating pawl for controlling the operative relation between said pawls and the ratchet.

6. In a lifting jack of the class described, a frame, a ratchet mounted on said frame 15 having a work engaging element associated therewith, an actuating handle pivoted to and operable externally of the frame, an actuating pawl movable in response to the actuation of said handle for effecting movement of the ratchet, a locking pawl having a fixed pivotal mounting, and a horizontally 20 shiftable member adapted to be moved in response to the longitudinal movement of the actuating pawl to permit the locking pawl to become operatively associated with the ratchet, whereby said ratchet will be locked in position upon the disengagement of the actuating pawl.

7. In a lifting jack of the class described, a frame, a pawl and ratchet mechanism mounted upon said frame, said mechanism including a ratchet quadrant having a work engaging member, an actuating pawl for moving the quadrant, a locking pawl for engaging the quadrant when the actuating pawl is disengaged, means connected with said actuating pawl and operable externally of the frame for effecting operation of said pawl and ratchet mechanism, resilient means for 40 urging said pawls toward the teeth of the ratchet, a slideable member operatively associated with said pawls for controlling the direction of movement of the quadrant in response to the actuating of the means connected with the actuating pawl, and resilient means for urging said slideable member in one direction to cause the disengagement of the locking pawl from the ratchet teeth.

8. In a lifting jack of the class described, 50 a frame, a pawl and ratchet mechanism mounted upon said frame, said mechanism including a ratchet quadrant pivotally mounted at the upper end of the frame and formed with a lateral arm adapted to be swung to a low position to permit the same to be positioned beneath a device to be elevated, an actuating handle pivoted near one extremity and at the lower portion of said frame, an actuating pawl pivotally mounted 55 upon and longitudinally movable in response to the actuation of said handle, means for normally urging said actuating pawl toward the teeth of the ratchet, a locking pawl having a fixed pivotal mounting at the lower portion 60 of the frame, resilient means for urging

said pawl toward the teeth of the ratchet, and a horizontally shiftable member associated with said pawls, said member serving as a means for controlling the operative positioning of said pawls with respect to the ratchet teeth so as to govern the direction of movement of the ratchet in response to the actuation of the handle. 70

9. In a lifting jack of the class described, a frame, a pawl and ratchet mechanism mounted upon said frame, said mechanism including a ratchet quadrant having a work engaging member, an actuating pawl for moving the quadrant, a locking pawl for engaging the quadrant when the actuating pawl is disengaged, means connected with said actuating pawl and operable externally of the frame for effecting the operation of the pawl and ratchet mechanism, a slideable member having a projection engageable by the actuating pawl, whereby said actuating pawl may be disengaged from the ratchet teeth, another portion of said slideable member being adapted to engage the locking pawl to effect the disengagement thereof from the ratchet mechanism, and resilient means for normally urging said pawls into operative engagement with the ratchet teeth. 80 90

10. In a lifting jack of the class described, a pair of side frames, said side frames converging upwardly to present a bearing, a ratchet device mounted in said bearing, said ratchet device having a lateral arm adapted to be swung to a low position to permit the same to be positioned beneath a device to be elevated, rollers supporting said side frames, an actuating handle pivotally mounted between and extending outwardly from said side frames, an actuating pawl pivotally mounted upon the pivoted end of said handle and adapted to be longitudinally moved in response to the actuation of said handle to effect movement of said ratchet device, a locking pawl pivoted in a fixed position between said side frames at the lower portion thereof, resilient means interposed between said locking pawl and said frames for normally urging said pawl into engagement with said ratchet, resilient means interposed between said actuating pawl and said frames for normally urging said pawl into engagement with said ratchet, a member slidably mounted between said frames in operative association with said pawls, said member being adapted to independently effect the disengagement of said pawls from the ratchet to control the direction of movement thereof, and means operable from a point on the handle for controlling the movement of said slideable member. 100 110 120 125

11. In a lifting jack of the class described, a pair of side frames, said frames converging upwardly to present a bearing, a ratchet quadrant mounted in said bearing, said quadrant having a laterally extending lifting arm 130

adapted to be swung to a low position to permit of its being positioned beneath a device to be elevated, a work engaging member pivotally mounted at the extremity of said arm, a 5 link interposed between said pivoted work engaging member and said frames to maintain the horizontal position of said work engaging member during the movement of said ratchet quadrant, an actuating handle 10 pivoted between said side frames, an arm extending laterally from the pivotal point of the handle, an actuating pawl pivotally mounted at the extremity of said arm, resilient means for urging said pawl into operative engagement with the teeth of said 15 ratchet, a locking pawl pivotally mounted upon a fixed bearing extending between the lower portion of said side frames, resilient means for normally urging said pawl into engagement with said ratchet teeth, a horizontally shiftable member mounted upon 20 means extending between said side frames, resilient means for urging said member in one direction to effect the disengagement of the locking pawl from the ratchet, said shift- 25 able member being operable, in response to the movement of the actuating pawl in one direction, to permit the locking pawl to engage the ratchet teeth and to disengage the actuating 30 pawl from said ratchet teeth, and means operable on the actuating handle for controlling the movement of said shiftable member.

12. In a lift jack of the class described, a frame, a pawl and ratchet mechanism 35 mounted in said frame, said mechanism including a quadrant having work-engaging means, means for controlling the movement of said ratchet quadrant associated with the frame, a tiltable member mounted in said 40 frame, an actuating pawl pivotally mounted on said tiltable member and operable in response to the movements of said tiltable member to impart movement to said ratchet quadrant, a locking pawl having a fixed pivotal 45 mounting, and means including a horizontally disposed slideable bar for engaging the actuating pawl when in one position and the locking pawl when in another position to control the direction of movement of the 50 ratchet quadrant.

13. In a lift jack of the class described, a frame, a pawl and ratchet mechanism mounted in said frame, said mechanism including a quadrant having work-engaging 55 means, means for controlling the movement of said ratchet quadrant associated with the frame, a tiltable member mounted in said frame, an actuating pawl pivotally mounted on said tiltable member and operable in 60 response to the movements of said tiltable member to impart movement to said ratchet quadrant, a locking pawl having a fixed pivotal mounting, means including a slotted horizontal shiftable member 65 for controlling the direction of movement of

the quadrant, and means extending through the slots in said member for supporting and guiding said member during its horizontal movement.

14. In a lift jack of the class described, a frame, a pawl and ratchet mechanism mounted in said frame, said mechanism including a quadrant having work-engaging means, means for controlling the movement of said ratchet quadrant associated with the frame, a tiltable member mounted in said frame, an actuating pawl pivotally mounted on said tiltable member and operable in response to the movements of said tiltable member to impart movement to said ratchet quadrant, a locking pawl having a fixed pivotal mounting, a slideable member for engaging the pawls to control the direction of movement of the quadrant, and a pair of spaced supporting members upon which said member is slideable.

In witness whereof, I have hereunto subscribed my name.

MILLARD B. LUCKER.
